UNITED STATES PATENT OFFICE.

ERNST WOLTMANN, OF NEW YORK, N. Y., ASSIGNOR TO AUTOMATIC TRAIN STOP COMPANY, A CORPORATION OF MAINE.

ELECTRIC TRAIN-CONTROL SYSTEM.

1,111,344.

Specification of Letters Patent. Patented Sept. 22, 1914.

Application filed December 7, 1908. Serial No. 466,253.

To all whom it may concern:

Be it known that I, ERNST WOLTMANN, a citizen of the United States, residing at the city of New York, in the borough of 5 Queens and State of New York, have invented certain new and useful Improvements in Electric Train-Control Systems, of which the following is a full, clear, and exact description.

10 My invention relates to train control systems, being a system or installation by which signals and other prescribed traffic conditions are automatically enforced. In my prior Patent No. 875,028, granted Dec. 31, 1907, I have set forth an installation of this character having certain broad features or principles by which a sectional third rail or trolley of an electric railroad is made use of as a line conductor for the power current 15 transmission. In other words I have provided an electric train or trolley system which may be said to have as its prominent characteristics: First, a trolley, power or third rail which is sectionally divided so 20 that any desired portion may be cut out or rendered non-electrified at will. Second, a signal or order enforcing train stop operating in conjunction with the foregoing sectional power rail, and third, a means by 25 which the considerable current-carrying capacity of the third rail or trolley is made use of for the power current transmission. This third feature or characteristic is set forth at length in my above prior patent to which 30 reference may be made for a full description.

Briefly recapitulated, it may be stated that 35 an electric road is a power transmission system in which the electric energy is carried for long distances in a conductor, and as a 40 third rail has great current carrying capacity, it is extremely advantageous to make use of it for actually transmitting the current of the system from a distant point, as 45 well as its obvious function of furnishing a contacting member for a train at any particular point. I accomplish this broadly 50 stated purpose in my prior patent, and in the present application, in conjunction with 55 other features and purposes. In the present application, I have attempted to provide for every sort of traffic condition or contingency 60 which can arise, enforcing the signals or orders by an automatic train stop in all cases, besides securing all the ordinary well

known advantages of a sectional third power rail or trolley and the above power transmitting purposes; making reliance on the human factor in the service as absolutely negligible as can be done by any equipment. 60

With the foregoing and other objects in view, my invention consists in the features of construction and combination as herein-after set forth and claimed.

In the drawings: Figure 1 is a diagrammatic view of an installation embodying the principles of my invention, and Fig. 2 is a detail view showing certain features in the wiring on the motor car or vehicle. 65

Referring to the drawings in which like parts are designated by the same reference sign, 1 designates trackways of which two are shown in the drawings, it being evident that as many trackways as are available will be joined in the system. Almost all electric 70 roads have at least two trackways, and very commonly a much greater number. Each trackway has a usual third rail or trolley 2. The third or power rails ordinarily employed are heavily made of iron to stand the 75 rough usage to which they are exposed in the engagement of the contact shoes of trains and in other ways, so that they necessarily have large current carrying capacity: that is to say, each power rail, if continuous 80 throughout its length, is adapted to serve admirably as a line conductor for the power transmitting system. To illustrate by a practical example, supposing that an ordinary iron rail has a current carrying capacity 85 of 200 amperes for every square inch of its transverse sectional area, without undue loss from ohmic resistance and heating, it is evident that an average contact rail of the kind usually employed, if continuous, will 90 be capable of transmitting about one or two thousand amperes from a distant power station to the various distributed trains along the roadway. It is practically very important to have the third or power rails made in 95 sections which can be independently cut out when desired, which, of course, ordinarily prevents their service as a line conductor in the above manner. 100

By my invention I make the various third or power rails of the different track ways sectional, and still constituting the line conductors for the power current transmission for the system by combining them together along their lengths and between the different 110

trackways. Any particular section may be cut out under these circumstances, without in any way disturbing the current carrying function of the system as a whole. In the 5 particular illustration of the present case, track rails 1, are divided into blocks denominated A, B, C and D, and the third rails 2, 2', are in sections of corresponding lengths along each track way. All of the sections 10 are normally interconnected both along the same trackway and along different trackways, so they form in effect a single system of power distribution. The connection between the adjacent rail sections 2 of the same 15 trackway, is established through branch wires 3 and switches 4. The connection between the sections of the adjacent or different trackways is established through the cross wires 5, normally joining all the adjacent 20 rail sections at each block entrance or section.

The various switches 4 are capable of being opened so as to cut out any selected third rail section. The means which I have adopted for operating the switches 4, is dependent upon the semaphore signal system, and is operated for the purpose of enforcing the observance of the danger signals by the automatic stoppage of the train. The semaphore 25 system may be of any ordinary or desired character, such, for example, as shown in my patent referred to. I have merely diagrammatically indicated the semaphore signals at B', C' and D', they being merely 30 ordinary signals with switches b, c, d, to close certain circuits when the semaphores come to danger. These circuits closed by the movements of the semaphores to danger, are denominated 1', 1², 1³, respectively, each 35 being independent of the others. These circuits effect the opening of the switches 4 in such a way as to cut out the requisite third rail sections to absolutely enforce the observance of danger signals under all circumstances. 40

10 denote latches which restrain the switches 4 in their circuit closing relations against the tension of springs or equivalent means 8, which are adapted to open the 45 switches 4, when the latter are released by the latches. The latches 10 are displaced to release the switches by magnets which may be arranged in any desired way. I have illustrated each switch actuated by a sectionally wound magnet 11 in the present case, there being three independent windings or sections, preferably provided. These sections are in the circuits of the semaphore operated circuit closers b, c, d, as follows: 50 A given magnet 11, say at the entrance to block B, has one section 11' in the circuit 1' of the semaphore operated circuit closer b, which circuit is continued through section 11² of the next block C and section 11³ of 55 the following block D. In like manner the

sections 11^x of magnet 11 at entrance to block C is in the contact 1² of the semaphore operated circuit C, and is continued through the middle section of the third magnet 11. This relation is uniform throughout the 70 system and may be generally described that the semaphore operated circuit closer at the entrance to each block is adapted to complete a circuit which trips not only the latches 10 at the ends of its own block, but also the latches of the following block, three 75 latches in all, cutting out two third rail sections. These circuits derive their current from the collector shoes of the trains. Where the power current has a ground return, as is the usual practice, the ground 80 may be made use of as a return for these latch tripping circuits, by simply grounding their terminal ends at g, in an obvious manner. 85

13 denote contacts along the trackway at the entrances of the various blocks. These contacts are in the path of the usual collector shoes of the train, and as such collector shoes are ordinarily arranged in duplicate 90 on both sides of the motor cars, it is convenient to have the contacts 13 located on the opposite side of the trackway from the regular third rail. The most satisfactory plan is to fix a single length of rail on the 95 off-side of the trackway in exactly the same way that the regular third rail 2 is mounted on the other side. The circuits 1', 1² and 1³ extend from these contacts 13 through the sections of the magnets 11, and through the semaphore operated circuit closers a, b, c, being finally completed to ground at g in the manner already described. Sections on as many magnets as desired may be included. Before taking up the operation I will refer 100 to two additional features of my invention which are incorporated in the illustration. 105

Reference has been made to the fact that the third rails 2 are divided into sections corresponding to the blocks of the trackway, 110 but the divisions 15 of the third rails are not opposite to the entrances of the respective blocks, at which the semaphores B', C', D', and the contacts 13 are located. The third rail gaps or divisions 15 are spaced 115 back from the block entrances, for a distance greater than the separation of the extreme collector shoes of the longest train. The second additional feature just referred to lies in the provision of distant control circuit openers B^x, C^x and D^x, in the various 120 circuits 1', 1² and 1³. These circuit openers are ordinary distant control switches and are all located in a single operating or pilot circuit p, in such a way that they are all 125 simultaneously actuated together, so as to open the various circuits 1', 1² and 1³. The operating or pilot circuit p extends along the entire length of the traffic division between the train despatcher's stations, or 130

more exactly, between the various flag stations which are in telegraphic communication with the despatcher's station. The result is to put all of the distant control circuit openers under the supervision of the main train despatcher, through the subordinate flag officers along the road.

I will now consider the operation under the usual traffic conditions which arise, and show that I satisfy all ordinary conditions and provide for the absolute enforcement of the danger signals without either interfering with the current carrying functions of the third rail, or tying up the whole system when the train stop operates at any particular point.

I will assume that a train is moving from right to left in the direction of the arrow and that the block B is already occupied by a train, throwing the semaphore B' to danger in the usual way. The movement of the semaphore at the entrance to block B to danger causes the semaphore-operated circuit-closer b to close the circuit 1' at such point and this circuit includes the sections 11', 11² and 11³ of three successive latch-tripping magnets 11. Assuming that this signal is disregarded by the following train the latches at both ends of blocks B and C will be therefore simultaneously tripped or attracted and the switches 4 simultaneously moved to open-circuiting position. The result is that the third-rail sections 2' generally opposite blocks B and C are entirely cut out and rendered non-electrified. This action does not occur, however, until the first collector shoe of the following train has engaged the contact 13, or in other words until the front of the train is opposite the semaphore B'. Inasmuch as the divisions 15 of the third-rail are spaced back from the block entrances for a greater distance than the length of the longest train, it follows that any succeeding train which proceeds beyond the semaphore B' at danger, at once loses its power current on account of the non-electrification of its entire available length of third-rail section. As will later appear the brakes are simultaneously applied, corresponding to an absolute train stop. The observance of the danger signal B' is therefore positively and automatically enforced.

It is necessary to consider all possible positions of the train which already occupied block B in the above action. It might happen that such train was nearly emerging from the block, but not entirely past the third-rail gap 15 between B and C. If the advance train was stalled in this position, the third-rail sections of blocks B and C would be virtually connected together through the shoes of such train, but this fact would not interfere with the train stop operation above described, because both

of such third-rail sections were cut out when the following train moved past the danger semaphore B'. In other words the following train cannot obtain current to disobediently pass a danger signal because the advance train on the same block happens to occupy a position which bridges or connects together the third-rail section of such block and that of the block in advance. It is therefore not possible for the following train to derive current from the electrified block behind, due to its own length (within ordinary limits) or by reason of the position or length of the train in front. The danger signal is therefore absolutely enforced under all circumstances.

I will now consider the manner by which the remainder of the railroad is not tied up by the foregoing actuations. The third-rail sections of blocks A and D have not been cut out in the above action and are still electrified. These sections are moreover connected through the leads 5 to the third-rail 2' of the adjacent track, which is virtually continuous at this time inasmuch as the various switches 4 thereof are presumably closed. The third-rail 2' therefore is in a position to carry the line current transmission past the blocks B and C. The imposition of the entire current on this single third-rail might overload it somewhat and entail a loss of power, but this is of no consequence as the action is only occasional or extraordinary in its character and temporary loss under such extraordinary circumstances is a negligible factor. If there are more than two trackways, as is commonly the case, the current carrying capacity of the system is reduced in a much less ratio. For instance, if there are three tracks, the current carrying capacity is decreased 33 $\frac{1}{3}$ per cent instead of 50 per cent. If there are four tracks, the loss in current carrying capacity is only 25 per cent, etc. It is therefore apparent that the railroad system as a whole is not tied up in any way by the foregoing actuations. Also it is evident that even with only a single trackway there is no tie-up of the system in ordinary practice because the line or power conductor is ordinarily fed from both ends of the system.

In all electric systems provision must be made for grounds and short circuits and failure of the apparatus and other extraordinary conditions; for example, in case of a wreck, the wrecking train has to go past a semaphore at danger and creep up to the actual point of the stalled or wrecked train. For these conditions I provide the distant control circuit openers B^x, C^x, D^x, which are in pilot or operating circuits under the direct control of the train despatcher and his flag officers. Upon orders from the despatcher (who suspends all rules when he de-

sires) the flag officers may open all the distant control switches of their road division, which has the effect of preventing any current flow through the various circuits I^1 , I^2 and I^3 , and the actuation of any of the train stop devices in the manner above described. This control therefore imposes a supervision on the system from the dispatcher's office, by which he can suspend its operation when necessary, an important and desirable feature in practice.

In order to avoid the necessity of manually restoring the various switches 4 to their closed circuit positions when they have been tripped, I provide means for doing this automatically. I have chosen to employ time element controlling means for this purpose which serves to automatically restore any switch 4 to its normal closed circuit position a certain definite time interval after it has been tripped; for example, after an interval of one or one and one-half minutes. If the conditions have not become normal during this interval, the switches 25 may be tripped again and so on as long as the abnormal conditions continue, but when normal running conditions are restored, the switches finally remain closed. Many forms of mechanism may be adapted for this purpose. I have illustrated more or less diagrammatically a mechanism employing solenoid magnets 20 acting on armatures or plungers 21 which have projecting stems 22 adapted to impinge against the switch 35 blades 4 and move them to circuit closing and latching position.

23 denote dash-pots to constrain the plungers in a very slow movement in their action of closing the switches 4. The 40 plungers are returned by springs 24. 25 designates a circuit which may receive current from any suitable source and which includes the magnet 20, the latch 10 and a contact 26 which is engaged by the latch when 45 the latter drops by reason of its non-engagement with the switch lever 4 (accompanied, of course, by a cessation of the attraction of the magnet 11). Under these circumstances the solenoid will be energized and the 50 plunger 21 drawn toward the right so as to move the switch blade 4 to its circuit closing relation. If the magnet 11 continues to be energized, the above circuit closing will not occur, but it will be observed that this 55 is as it should be, since the magnets 11 will not continue energized when the conditions have become suitable for the re-closure of the switches 4.

The disregard of a danger signal is unusual and of such serious import that it is imperative that the train dispatcher should know of such occurrence. This system has been devised with this feature in view and in the event of such disobedience 65 whereby for example a train on block B,

having set semaphore B* at danger, is followed by a train which disregards such signal and attempts to enter block B, the current being cut off from both of said blocks in the manner hereinbefore described 70 necessitates communication with the train dispatcher's office in order that he may permit the said trains to proceed to causing the respective semaphores in question to be lowered. This cuts out the magnets 75 11 and the switches will thereafter automatically close.

I have referred to the fact that the train stop actuations above described are specially enforced and made positive by the application of the air brakes. I accomplish this by means which also prevents any blowing of the train fuses from interfering with the train stop functions. Referring particularly to Fig. 2, 30 denotes a motor 85 car having collector shoes 31. Ordinarily four collector shoes, two on each side, are provided. In accordance with the usual practice, each collector shoe has a safety fuse 31 in its connection with the other 90 collector shoes and with the train motors so that short circuits will not cause damage. These fuses are, of course, liable to be blown at any time from various causes, and in the absence of special circuits, it may 95 happen that two or more fuses might be blown, or some other disconnection occur, in such a way that the contacts 13 would not receive current. In order to insure that the collector shoes which engage the contacts 13 are electrified, regardless of the blowing of their fuses or other disconnection, I connect all the collector shoes together with circuit wires q in which resistances of say fifty ohms are interposed. 105 The best plan is to join each collector shoe to a common point of connection 33, and in each branch to impose a resistance of about half the total value required. With this arrangement each collector shoe is 110 capable of deriving current through the circuit wires q from one or more of the remaining collector shoes, but it is not possible for this current to pass by any way or combination of ways without traversing 115 at least two of the resistance branches referred to. As these resistances are sufficiently great to limit the current flowing to a value within the capacity of the conductor employed, it follows that the circuit wires q are not liable to be burned out even if one collector shoe should be directly grounded while another shoe is resting on the power rail. The circuit connections q 120 may therefore be considered as permanent and reliable factors in the installation, insuring the electrification of all the shoes whether or not their fuses happen to be blown. The current derived in this way is perfectly sufficient for the operation of 125 130

the tripping magnets 11 which are wound to employ only a light operating current. Connected to the system of the collector shoes 31 is a ground circuit *r* in which is located a magnet-operated train-pipe release valve 40. The cutting out of any third-rail section results, of course, in the immediate non-electrification of the train collector shoes and this fact causes a failure of current in the magnet-operated train-pipe release valve 40. Magnet-operated train-pipe release valves which open the train-pipe upon failure of current in a circuit, are well known and I have not therefore particularly illustrated such a mechanism. Any ordinary device of this character may be inserted in the circuit *r* and will operate with my invention.

Having described my invention, I claim:

20 1. An electric railway system having substantially parallel trackways, a sectional power conductor for each trackway, switches normally joining the ends of the sections of the conductors together into a plurality 25 of unbroken series, one series for each trackway, means for electrically connecting the switches of adjacent trackways, and means operating to open three of said switches at a time, said switches so opened being 30 those at the respective ends of two aligned power conductor sections.

2. An electric railway system having substantially parallel trackways, a sectional power conductor for each trackway, switches 35 normally joining the ends of the sections of the conductors together into a plurality of unbroken series, one series for each trackway, means for electrically joining the switches of adjacent trackways, and means 40 operating to open a plurality of said switches of one series simultaneously, said switches so opened being those at the respective ends of a one less number of aligned power conductor sections.

45 3. An electric train control system having a sectional power conductor, means for normally joining the sections of the power conductor in unbroken continuity, contact pieces along the track-way, each of said 50 contact pieces spaced from and in advance of the division point of two adjacent sections of the power conductor, a train having a collector shoe at one end thereof adapted to contact with the sections of said 55 power conductor, a second collector shoe electrically connected to said first named shoe and located at the other end of the train and adapted to contact with said contact pieces, said shoes being spaced apart a 60 distance less than the distance between a contact piece and the corresponding, division point of the sections of the power conductor and means controlled by the passage of said second named collector shoe over

65 a contact piece for cutting out the section

of the power conductor opposite the last named contact piece.

4. An electric train control system having a sectional power conductor, means for normally joining the sections of the power conductor in unbroken continuity contact pieces along the track-way, each of said contact pieces spaced from and in advance of the division point of two adjacent sections of the power conductor, a train having a collector shoe at one end thereof adapted to contact with the sections of said power conductor, a second collector shoe electrically conducted to said first named shoe and located at the other end of the train adapted to contact with said contact pieces, said shoes being spaced apart a distance less than the distance between the contact pieces and the corresponding division points of the sections of the power conductor and means controlled by the passage of said second named collector shoe over one of said contact pieces for cutting out the sections of the power conductor opposite the last named contact piece and the section in advance thereof.

5. An electric train control system having a sectional power conductor, a trackway having block entrances, switches for connecting the ends of said sections in unbroken continuity, normally open circuits, means for closing them, means controlled by each of said circuits when closed for opening three consecutive switches to cut out two adjacent conductor sections, and means in each of said circuits controlled from a distance to open said circuit at a point distinct from the point at which it was closed by said first mentioned means together with means for moving each of said switches to closed position after said circuit has been opened by said means controlled from a distance.

6. An electric train control system having a sectional power conductor, a trackway having block entrances, contacts at such entrances, means on the train for electrifying said contacts, switches for connecting the ends of said sections in unbroken continuity, circuits, means controlled thereby for opening said switches three at a time, each of said circuits deriving current from a particular contact, and means for closing said switches substantially simultaneously, said last mentioned means including a circuit controlled from a distant point.

7. An electric train control system having a sectional power conductor, switches for connecting the ends of the sections of said conductor in unbroken continuity, means for opening a plurality of said switches together, and means including a time controlled device for closing the switches.

8. An electric train control system hav-

ing a sectional power conductor, switches for joining the ends of the sections of said conductor in unbroken continuity, means for opening said switches, three consecutive ones at a time, whereby two adjacent sections of said conductor are cut out of circuit and means including a time controlled device for closing the switches.

9. An electric train control system having a sectional power conductor, switches for joining the ends of the sections of said conductor in unbroken continuity, means for simultaneously moving a plurality of said switches to open circuiting position, 10 circuits controlled by the opening of said switches, and magnetic means actuated by said circuits for closing such switches, said magnetic means having time controlled means associated therewith whereby the 15 closure of said switches is retarded for a certain interval.

10. An electric railway system having adjacent trackways, a sectional power conductor for each trackway, switches normally joining the ends of the sections of the conductors together into a plurality of unbroken series, one series for each trackway, means for electrically joining the switches of adjacent trackways, means operating to 25 open a plurality of said switches simultaneously corresponding to a particular power

conductor section and time controlled means for closing said switches.

11. In an electric railway system, a sectional power conductor, switches normally joining the ends of the sections together in an unbroken series, means actuated by the presence of two trains spaced apart less than a predetermined distance for opening said switches in groups, and electrically 35 operating means actuated by the restoration of normal traffic conditions of the trains for restoring said switches to close their circuits.

12. In an electric railway system, a sectional power conductor, switches for joining the sections of said conductor together in an unbroken series, automatic means for simultaneously opening a limited number of successively disposed switches 40 upon the presence of two trains spaced apart on the blocks of the track less than a determined distance, and electrically controlled means for closing said switches, when opened, at will from a point remote from 45 said switches.

In witness whereof, I subscribe my signature, in the presence of two witnesses.

ERNST WOLTMANN.
